UNITED STATES PATENT OFFICE.

THOMAS L. DENNIS, OF NEW YORK, N. Y.

TYPE-WRITING MACHINE.

No. 860,643.

Specification of Letters Patent.

Patented July 23, 1907.

Application filed December 2, 1904, Serial No. 235,242. Renewed November 13, 1906. Serial No. 343,289.

To all whom it may concern:

Be it known that I, THOMAS L. DENNIS, a citizen of the United States, and a resident of the borough of Manhattan, in the city, county, and State of New York, 5 have invented certain new and useful Improvements in Type-Writing Machines, of which the following is a specification.

My invention, while relating to that class of type-writing machines in which the types that form the letters or other impressions are carried upon the free ends of swinging levers or "type-bars" so called, has reference more particularly to that form of such machine in which the type-bars are so mounted that, when properly operated, they swing their respective types downward upon 10 the paper or other material as it is supported upon the paper carrying cylinder, to make their respective impressions thereon, and are then swung backward therefrom to allow of the writing or printing being exposed to the view and inspection of the operator as soon as the 15 several impressions are made; the objects of the invention being to provide a machine of this class, which, while greatly simplified and thereby materially cheapened in the cost of manufacture, shall at the same time be more efficient in operation and less liable to get out 20 of adjustment and repair than those heretofore in use.

To these ends the invention consists, first, in the means by which the several type-bars are connected with and operated from their respective actuating key-levers; second, in the means by which the several type-bars and their connections with their respective actuating key-levers are mounted and supported in or upon the machine, and third, in various other constructions and combinations of parts, all as will hereinafter more fully appear.

Referring to the accompanying drawings which form a part of this specification, Figure 1, is a vertical longitudinal section of the machine, taken in the line $z z$ of Fig. 3; Fig. 2, a similar vertical longitudinal section thereof taken in the same line as Fig. 1, but showing certain of the parts in a slightly different position; Fig. 3, a plan view of the machine, with various of its parts removed, others broken away for convenience of illustration, and others shown in dotted lines; Fig. 4, a plan view of one of the intermediate levers by means of which the type-bars are connected with the actuating key-levers, detached; Fig. 5, a plan view of one of the blanks from which the intermediate levers are formed, and Fig. 6, a section of one of the type-bars taken in the plane $y y$ of Fig. 2.

In all the figures like letters of reference are employed to designate corresponding parts.

A indicates the frame work or housing of the machine, and B indicates the cylinder upon which the paper or other material receiving the impression of the type is supported and carried during the type-writing operation. The frame work or housing A may be con-

structed in any approved form that will adapt it to receive and support the various parts of the machine, and the cylinder B may, in practice, be mounted in a suitable carriage, which, through appropriate mechanism, is caused to move forward in the direction of its length by a progressive step by step movement, to not only feed the paper or other material to the action of the successive types, during the type-writing operation, but to properly space the intervals between the successive 60 impressions made by them and between the successive words, as is usual with type writing machines as heretofore constructed. This carriage and the mechanism by which its movements are effected however constitute no part of my present invention. They have 65 therefore been omitted from the drawings, and a further description of them herein is not considered necessary.

C indicates the type-bars which are normally held in upwardly and outwardly inclined positions, and are arranged in a circular row concentric to a common center located at or near the upper surface of the cylinder B, at the point marked * with each of the bars disposed in radial relationship thereto, and provided on its inner edge at or near its outer end with one or more of the types c with which the machine is or may be equipped. 70 As thus disposed and provided, the printing is effected by swinging these type-bars towards and downward in the required order upon the paper or other material supported upon the cylinder B, until their respective types are brought into contact with it; and in order to insure of the successive types being brought into the exact position to imprint or impress their respective letters or characters in the required location, the lengths of the type-bars are so proportioned as to bring them into that relationship when the types are carried forward into 75 contact with the paper or other material.

For supporting the type-bars and permitting of their swinging movement toward and away from the cylinder B, I make use of a stand D, which is constructed in the form of an arc of a circle and is provided with radially 80 disposed slots d formed therein in which the type-bars are pivoted by a wire d¹, which passes through a suitable orifice formed in or near the lower end of each, and is itself secured in an orifice d² formed near the top of the stand near the outer surface thereof. As thus constructed this stand is secured to or formed upon the upper surface of a supporting plate or base E, which extends transversely across the frame work or housing A, from one side thereof to the other, and either made integrally therewith or detachable therefrom and secured at its ends to the upper edges of side walls of the same by screws e or otherwise, is so disposed upon these side walls as to bring the stand carried by it into concentric relationship with respect to the center of impact of the various types c against the cylinder B, marked * 100 in Fig. 3, as these types are brought into contact with it.

With the type-bars arranged and supported as above

explained, the swinging of these bars toward the cylinder B to make the required impressions upon the paper or other material, or to meet other demands thereon, is effected by key-levers F, of which there is a separate lever employed in connection with each type-bar. These key-levers are preferably arranged side by side within the lower portion of the frame work or housing A, and are pivoted at their rear ends upon a rod f, which extends transversely across the frame work or housing, 5 near the rear of the latter, and is secured at its opposite ends in the side walls thereof. From the rod f these key-levers extend forward to the front of the machine and are provided upon their forward upturned ends with appropriate key or finger-pieces f¹, through 10 which the depressions of the free forward ends of such levers may be effected when desired. As thus disposed, each of these key-levers F is connected with its respective type-bars C through the intervention of an intermediate lever H, which is provided at its inner end 15 with a pin or roller h that engages with a slot c¹ formed in the lower enlarged end of the type-bar C, and is attached at its outer rear end to a key-lever F by a connecting rod I. The intermediate lever H, being thus arranged and connected, is fulcrumed near its middle 20 point in a stand L, which is preferably constructed in circular form and is secured to or formed upon the upper surface of the plate or base E, in concentric relationship to the stand D, with a series of radially disposed slots l formed therein to register therewith or in prolongation of the slots d in the stand D, whereby, in the construction of these parts, the formation of each of the 25 slots in both of the stands may be effected at one and the same milling operation. Within the slots l, as thus formed, are fulcrumed the respective levers H upon a wire l¹, which extends through a suitable orifice or bearing l¹ formed in each, and is itself secured in a suitable orifice l², formed near the outer surface of the stand L and near the top thereof, as shown.

In the construction of the levers H various forms 30 may be adopted. I prefer however to construct them from sheet metal and to provide them alike with bifurcated inner ends and with open fulcrumed bearings l¹, whereby to permit, not only of the pivoting of a friction roll h between the inner ends of the branches of each, and of the movement of the lower ends of their respective co-operating type-bars between their inner 35 projecting branches, but of the ready removal and replacement of the levers from and upon their fulcrumed wires l² when desired. When this form of construction 40 is adopted, a blank H¹ for each, of the form of that shown in Fig. 5, is first struck up from, or pressed out of, sheet metal, with a slot h¹ formed in its inner end, and an aperture h² of approximately heart shape to form the open fulcrumed bearing l¹ located near its middle point.

As thus constructed, this blank is then folded upwardly 45 along a longitudinal central line, as shown, for instance, by the dotted lines l⁴ in Fig. 5, with the result that the portions on opposite sides of this line will be brought together into the form of a bar, and an open bearing l¹ of the contour of that shown in Figs. 1 and 2 produced. The transformation of the blank up to this point having 50 been accomplished, the portion of its inner end on opposite sides of the slot h¹ are then bent outward and then inward, whereby to dispose them in parallel relationship, as shown in Fig. 4, after which the orifice h² is

formed through their inner ends to receive the pivot of the roller h, the orifices h³ formed through the rear end of the blank to receive the upper end of the connecting rod I, and the roller h rotatively secured in place by riveting the ends of its supporting pivot in the orifices h², when the lever H is completed ready for use, and the same method of procedure followed throughout the entire series of levers H.

With the levers H constructed as above described and arranged in proper relationship within the machine, the roller h in the inner end of each is in engagement with the slot c¹ in its respective type-bars C, and travels upward along the same, as the rear end of its respective carrying lever H is depressed by the key-lever appropriate thereto, causing thereby the swinging forward of the type-bar toward the cylinder B; and in order to provide for accelerating the movement of the type-bar in thus swinging forward from its rearmost position, the slot c¹ in its lower end is preferably constructed in the form of an involute, with gradually decreasing radius from its outer to its inner end. The type-bars C having been thus swung forward to bring their respective types in contact with the cylinder B, are each returned to its rearmost position away from the cylinder, by means of a spring m, which is preferably constructed with an intermediate coil m and with two extending arms m¹ and m², of which the arm m¹ is provided with a loop at its outer end that engages with a stud c², projecting from the side of its respective type-bar, while the outer free end of its arm m² is overturned or provided with a hook, which engages with an orifice l⁴ formed in an upwardly extending portion of its co-operating lever H, as shown. With the type-bars thus provided with means for both swinging them forward towards, and backward away from, the cylinder B, the backward swinging movements of these bars are limited by a stop N, which is preferably formed from a strip of sheet metal bent in curvilinear form, approximately concentric to the supporting stand D, and is supported at the proper elevation from the frame work or housing of the machine, by upwardly extending standards or posts N¹, to the upper ends of which its own ends are secured by appropriate screws m³, with a buffer m⁴ secured to its inner face and preferably constructed of some sound-deadening material, such, for instance, as felt. While the backward swinging movement of the type-bars C is thus limited, and the intermediate levers H are disposed in radial relationship above the parallelly arranged key-levers F, substantial uniformity of leverage between these key-levers and the type-bars throughout the series is accomplished by connecting these key-levers with their respective co-operating intermediate levers H at different distances from their respective fulcrua. To allow of the accomplishment of this result, the orifices h³ in the rear ends of the intermediate levers H (of which there may be a single orifice or a plurality of orifices in each) are formed at different distances from the fulcrua of such levers. As thus arranged the connection of the upper end of the connecting rod I with the intermediate lever H at each end of the series as, for instance, at F¹, will be with the orifice h³ nearest the fulcrum of that lever, in which case the power arm of that lever and the weight arm of its co-operating key-lever will be the shortest. From these intermediate levers at

the extreme ends of the series, around to near the middle lever thereof, the power arms of the intermediate levers and the weight arms of the key-levers will be lengthened at the proper points by connecting the 5 upper ends of each of the connecting rods I with one of the orifices h^3 at a greater distance from the fulcrum of its appropriate intermediate lever and so on until the middle intermediate lever of the series is approached, and the power arm of that intermediate 10 lever and the corresponding weight-arm of its respective coöperating key-lever will then be at their greatest lengths; and the corresponding power arm of its respective coöperating key-lever at its shortest length. By this arrangement, as will be seen, not only will the 15 leverage of the key-levers upon their respective type-bars be thus rendered practically uniform throughout, but substantially the same extent of vertical movement of the key-levers, to bring their respective type-bars into contact with the cylinder B from their back- 20 ward limit, be also insured.

In like manner to provide for bringing each of the keys or finger-pieces f^1 into proper relationship with respect to the others, I find it convenient to construct the rods I, which connects the key-levers with their 25 respective coöperating intermediate levers H, with an adjustable capability whereby to permit of their being lengthened or shortened as may be desired. To this end I preferably construct the connecting rods of wire, and, in addition to a suitable loop at its 30 lower end for embracing the key-lever, and an overturned hook at its upper end for engagement with one or the other of the orifices h^3 in the intermediate lever H, I provide each at a point intermediate its ends with a single loop or a plurality of loops i , which is or are 35 more or less open as shown. As thus constructed, the lengthening of the rod or rods when required to lower its or their respective key or finger-piece, or keys or finger-pieces, will be effected by simply opening out the loop or loops in the particular connecting rod or 40 rods to a greater or lesser extent, by means of a screw driver or other suitable appliance inserted within the same and properly operated therein. On the other hand, the shortening of this rod or these rods when demanded to raise the key or finger-piece or keys 45 or finger-pieces may be accomplished by forcing together the sides of the appropriate loop or loops to the required extent, by compressing or bringing together the sides of the loop or loops by a pair of pliers or other appropriate appliance applied to the outside thereof, 50 all as will be readily understood. With the movements of the key-levers thus adjusted, I provide means whereby not only are the front ends of these levers held at the proper distances apart and guided in their vertical movements, but their upward movement 55 limited. The means which I have found the most convenient for this purpose consists of a vertically disposed plate O, which extends transversely across the frame work or housing of the machine from one side thereof to the other, and is secured at its ends 60 to the side walls thereof by screws o, which pass through suitable overturned ears o^1 formed on the ends of the plate and engage with correspondingly shaped threaded orifices in the side walls of the former. As thus disposed, this plate O is provided with a series of slots o^2 , 65 which extend upward from its lower edge to the proper

height and correspond in number with that of the key levers. Within each of the slots thus formed is arranged one of the key-levers F which is guided by the side walls thereof, being limited in its upward movement by the upper end o^3 of the slot, which is disposed at the same height as that of all the others. With the front ends of these key-levers thus held and guided, the rear ends of these levers are in like manner held at the proper distances apart by a similar vertically disposed slotted plate P, which extends 70 transversely across the frame work or housing of the machine, from one side thereof to the other, with its slots p for receiving the rear ends of the key-levers formed from the upper edge thereof downward to the proper distance; and instead of being secured to the upper edge of the side walls of the frame work or housing, this plate P is secured to the base thereof by screws p^1 , which pass through suitable orifices formed in overturned ears p^2 at its ends, and enter correspondingly shaped threaded orifices formed in the base of 80 the frame work or housing, as shown. By this arrangement of guides and stops, as will be seen, not only are the key-levers properly held and guided at both of their ends but the upward movement of each 85 limited thereby.

From the foregoing therefore it will be seen that I provide a construction in which, not only is the type-writing visible at all times during the writing thereof, except when the types are making their respective impressions, and the type-bars are carried forward in 90 contact with the paper or other material with a gradually increasing and easy movement, but, in consequence of the construction of the levers, intermediate the key-levers and the type-bar, the construction of the connecting rods between the key-levers and the intermediate levers, and the construction of the stands in which the type-bars and the intermediate levers are 95 respectively pivoted and fulcrumed, whereby the slots for receiving the respective type-bars and intermediate levers are disposed in radial relationship in 100 prolongation of one another, great cheapness in the cost of manufacture is attained as well.

Having now described my invention, and specified certain of the ways in which it is or may be carried into effect, I claim and desire to secure by Letters Patent 110 of the United States,

1. The combination, with an upwardly and outwardly inclined type-bar provided at its lower part with a slot which has a gradually decreasing radius from its outer to its inner end, a stand in which the lower end of the type-bar is pivoted, and a key-lever for operating it, of an intermediate lever provided with a pin and roller at its inner end for engaging with said slot, a second stand in which said intermediate lever is fulcrumed, a common base for both of said stands, which latter have registering radial slots, and a connecting rod for connecting the outer end of said intermediate lever with the key-lever, substantially as described.

2. The combination, with a series of upwardly and outwardly inclined type-bars, each provided at its lower end with a curvilinear slot which is of a gradually diminishing radius from its outer to its inner end, a curvilinear stand provided with a series of radially disposed slots in which the lower ends of the said type-bars are pivoted, and a series of key-levers by means of which such type-bars are swung forward, of a series of radially disposed intermediate levers each of which is adapted at its inner end to engage with a curvilinear slot in the lower end of its respective type-bar, a curvilinear stand provided with

4
a series of radially disposed slots in line with prolongations of the lines of the slots of the aforementioned stand and in which last-named stand said intermediate levers are fulcrumed, a common base for both of said stands, and devices by which the outer ends of said intermediate levers are connected with their appropriate key-levers, substantially as described.

3. The combination, with an upwardly and outwardly inclined type-bar, a stand in which its lower end is pivoted, a lever operatively connected at its inner end with the lower end of the type-bar, a stand in which this lever is fulcrumed, of a double-acting spring interposed between the said type-bar and the said lever and directly engaging both of these parts, and serving to return them to their normal positions after having been removed therefrom, substantially as described.

4. The combination, with a series of upwardly and outwardly inclined type-bars each provided with a slot in its lower end, a curvilinear stand provided with a series of radially disposed slots in which the lower ends of the said type-bars are pivoted, and a series of key-levers by means of which such type-bars are swung forward, of a series of radially disposed intermediate levers each of which is provided at its inner end with a pin and roller for engagement with the slot in the lower end of its respective type-bar, a curvilinear stand provided with a series of radially disposed slots in which such intermediate levers are fulcrumed, a series of springs connected at their opposite ends to said type-bars and intermediate levers, so as to act reversely on both, and devices by which the outer ends of said intermediate levers are connected with their appropriate key-levers, substantially as described.

5. The combination, with a series of upwardly and outwardly inclined type-bars disposed in radial relationship, and provided with a curved slot in the lower end of each, a curvilinear stand provided with radially disposed slots

in which the type-bars are pivoted at their lower ends, and a series of parallelly disposed key-levers by means of which the forward movements of the type-bars may be effected, of a series of radially disposed intermediate levers provided with a pin and roller in the inner end of each for engagement with the slot in the lower end of its respective type-bar, a curvilinear stand provided with a series of slots in which the intermediate levers are fulcrumed, and connecting devices whereby the connection of the outer ends of these intermediate levers with their respective key-levers may be effected at different distances from the fulcrum of both levers, whereby to render the leverage of the key-levers upon their respective type-bars substantially uniform, substantially as described.

6. The combination, with a series of key-levers, of a base provided with two concentrically arranged curvilinear stands which are both provided with radial slots, with the slots in one stand in line with and in prolongation of the corresponding slots in the other, a series of type-bars pivoted in one of said stands and provided at their pivoted ends with curvilinear operating surfaces of gradually decreasing radii from their outer to their inner ends, and a series of intermediate levers having their fulcrum in the other of said stands and adapted at their inner ends to act upon and coöperate with the curvilinear surfaces of their respective type-bars and connected at their outer ends with their respective key-levers, substantially as described.

In witness whereof I have hereunto set my hand this 25th day of November, 1904.

THOMAS L. DENNIS.
